Baker

[11] Patent Number: Des. 424,566

[45] Date of Patent: ** May 9, 2000

[54] **RADIO FREQUENCY COAXIAL TRANSMISSION LINE CONTACT RETAINING CLIP**

[75] Inventor: **Robert S. Baker**, Harrison, Me.

[73] Assignee: **Howell Laboratories, Inc.**, Bridgton, Me.

[**] Term: **14 Years**

[21] Appl. No.: **29/098,855**

[22] Filed: **Jan. 7, 1999**

Related U.S. Application Data

[62] Division of application No. 08/832,230, Apr. 6, 1997, abandoned.

CLAIM

The ornamental design for a radio frequency coaxial transmission line contact retaining clip, as shown and described.

DESCRIPTION

FIG. 1 is a top view of a radio frequency coaxial transmission line contact retaining clip, the bottom view being a mirror image thereof;

FIG. 2 is a front view of FIG. 1;

FIG. 3 is a left side view of FIG. 1;

FIG. 4 is a right side view of FIG. 1; and,

FIG. 5 is a back view of FIG. 1.
